UNITED STATES PATENT OFFICE.

RANSOM BAILEY, OF MILWAUKEE, WISCONSIN.

SMOKE-PREVENTER.

1,248,990.

Specification of Letters Patent. Patented Dec. 4, 1917.

Application filed January 28, 1916. Serial No. 74,790.

To all whom it may concern:

Be it known that I, RANSOM BAILEY, a citizen of the United States, and resident of Milwaukee, in the county of Milwaukee and State of Wisconsin, have invented certain new and useful Improvements in Smoke-Preventers; and I do hereby declare that the following is a full, clear, and exact description thereof.

10 This invention relates to the subject of fire boxes for furnaces and the like, and the primary aim of the same is to provide simple, novel, and thoroughly practical means for feeding heated air to the fire so that the heated air will commingle with the gases arising from the fire, and thereby produce a perfect combustion.

Generally speaking the invention contemplates the delivery of air under pressure and 20 highly heated to discharge outlets which may be in the form of nozzles, twyers, and the like, located in the fire box above the fire and relatively positioned so that the air jets meet at the center of the fire and spread 25 in the form of an air film directly over the fire, and cause the gases arising from the fire to commingle and thoroughly mix with the air, and through such commingling and mixing are entirely consumed, the result being 30 that a thorough and perfect combustion is obtained with an increase of heat and the entire elimination of smoke or soot.

I accomplish a thorough heating of the air by the provision of air supply pipe lines disposed longitudinally in the walls of the furnace, and in this connection the invention further contemplates the provision of a novel arrangement whereby an equal distribution of air pressure is procured in the series of 40 nozzles or twyers projecting from said supply pipe lines.

In producing an invention capable of carrying out the functions generally stated above, it will be understood, of course, that 45 the same may be embodied in various forms, one simple and thoroughly practical embodiment being shown in the accompanying drawings wherein—

Figure 1 is a vertical longitudinal sectional view of a furnace equipped with the improved means for feeding heated air to the fire.

Fig. 2 is a transverse sectional view taken on the line 2—2, Fig. 1.

55 Fig. 3, is a fragmentary horizontal sectional view taken on the line 3—3, Fig. 1.

In the simple form of the invention shown by the accompanying drawings, the air is discharged from oppositely disposed nozzles or twyers 1, embedded in the linings 2, and 60 walls 3 of the fire box, the nozzles 1 being arranged at a downward inclination so that the oppositely projected heated air jets will meet at approximately the center of the fire, as indicated by Fig. 2 of the drawings, and 65 by such meeting the air jets are caused to spread in the form of a film above the fire in a position to intercept the products of combustion and cause a thorough mixing of the said products of combustion and the air, 70 and such mixture being highly combustible is immediately consumed, thereby materially increasing the heat within the fire box, and eliminating smoke, soot, and offensive gases 75 that would otherwise result from the fire.

In order to assure a complete combustion of the mixed air and gases within the fire box, it is necessary that the air be highly heated when discharged onto the fire, and to assure of the air being in a highly heated 80 condition when so discharged, my invention contemplates the placing of the pipes 4 that connect with the nozzles 1, in such positions that they are always highly heated so that the air that enters the same is immediately 85 highly heated. As suggested by the accompanying drawings, the pipes 4 are embedded in the side walls 3 and disposed longitudinally of said walls, adjacent the linings 2 and the nozzles which are right-angular 90 branches of the said pipes, the connections being made by means of elbows and T couplings, or any other efficient form of connection. The pipes 4, as shown, may project through and outwardly of the facing plate 95 of the boiler, and connect with air supply pipes 5, said air supply pipes being suitably connected to the outlet of the blower 6.

In the present showing, embodying a pair of nozzles in each supply pipe line 4, and 100 embodying consequently a T coupling and elbow in each pipe line, it is noted that the pipe line is materially reduced between the T coupling and elbow, and this reduction serves to procure a uniform distribution of 105 pressure in both nozzles by choking the pipe line immediately forwardly of the first nozzle, with respect to the direction of flow of air. This reduction of the pipe line is particularly essential in view of the progressive 110 heating to which the air is subjected in passing through the pipe line, with a consequent

tendency to increase in pressure. Should more than two nozzles be employed, involving a series of T couplings therefor, the supply pipe line would be successively reduced 5 adjacent the plurality of T couplings.

The blower 6 may be located in any desired place or position, although it is more convenient to have the same adjacent the furnace, as such facilitates the control of the 10 blower by the attendant in charge of the furnace.

The supply pipe 5 may be equipped with controlling valves, as shown by Fig. 1 of the 15 drawings.

15 The invention, is, of course, not restricted to the use of pairs of oppositely disposed nozzles, as more could, and in some instances should be used. It is however, essential that the nozzles shall be oppositely disposed and arranged within the linings 2 and the walls 3, so that while they are protected by such linings and walls from the direct action of 20 the fire, they are always at a downward inclination, so that the air jets are projected 25 downward, and meet centrally of the fire and thereby form an air film with which the gases thoroughly mixed.

30 And it is also essential that the pipes 4 be so disposed that they are highly heated, and that important advantage of the invention is obtained by embedding the said pipes in the walls 3 in positions where they are always heated.

35 It will be clear from the foregoing that this invention is one that can be applied to any type of fire box, either by embedding the same in the fire box as the fire box is being constructed, or by boring or removal of

parts of walls and linings of fire boxes that have been in use.

40 It will be seen that this invention provides means whereby outside air is taken by the blower and conducted to the heated delivery pipes 4, and from said pipes 4, the air having been pre-heated by said pipes, is discharged into the fire box by the nozzles 1. This is a valuable feature of my invention, 45 in that the air after being heated is not subjected to the cooling influences of storage tanks or conducting pipes.

50 I claim:

The combination with a fire box, of a pair of pipe lines disposed longitudinally in the side walls of the fire box above the plane of the grate whereby to receive heat therefrom, 55 a series of nozzles connected with each pipe line and disposed transversely at an incline in the corresponding wall of the fire box to discharge downwardly thereinto, a forced air supply communicating with said pipe 60 lines, and said pipe lines being formed of a series of sections, the sections farthest from said air supply decreasing in diameter whereby to procure a uniform distribution 65 of the pressure in said nozzles substantially as described.

66 In testimony that I claim the foregoing and have hereunto set my hand at Milwaukee, in the county of Milwaukee, and State 70 of Wisconsin, in the presence of two witnesses.

RANSOM BAILEY.

Witnesses:

H. JOSEPH DOYLE,
M. E. DOWNEY.
